UNITED STATES PATENT OFFICE.

AMOS E. BURROWS, OF PICTURE ROCKS, PENNSYLVANIA, ASSIGNOR OF ONE-HALF TO ISAAC BARTON, OF WILLIAMSPORT, PENNSYLVANIA.

DAMPER-REGULATOR.

SPECIFICATION forming part of Letters Patent No. 581,334, dated April 27, 1897.

Application filed November 11, 1896. Serial No. 611,728. (No model.)

To all whom it may concern:

Be it known that I, AMOS E. BURROWS, a citizen of the United States, and a resident of Picture Rocks, Lycoming county, Pennsylvania, have invented certain new and useful Improvements in Damper-Regulators, of which the following is a specification.

My invention relates to improvements in automatic damper-regulating devices, and 10 more particularly to improvements in damper-regulating devices which are controlled by the pressure of steam in a steam-boiler or by a column of water which is acted upon by the steam in a boiler.

15 In the accompanying drawings, forming part of this specification and in which similar letters of reference indicate similar parts throughout the several views, Figure 1 is a central sectional elevation of my improved 20 damper-operating device, the levers being shown in elevation; Fig. 2, an enlarged central sectional elevation of the relief-valve; and Fig. 3, a side elevation of that part of the 25 stack which carries the damper, showing the lever for operating the same; Fig. 4, a side elevation of my regulator, showing its attachment to a boiler, part of the latter and its stack being shown in side elevation.

A is a pipe which is connected with the 30 steam or water space of a steam-boiler A' or with a water-column, the liquid within which is acted upon by the steam in the boiler; B, a valve-chamber, the upper part of which is inclosed by a diaphragm C. The pipe A is 35 connected with the chamber within the valve-casing, as shown.

D is a rod or upright carried by diaphragm C, the upper end of which is formed into a knife-edge E.

40 F is a pipe, one end of which is connected centrally with the under part of valve-chamber B, and the other end of which connects with a hydraulic cylinder G, which is fitted with a piston H, the rod I of which is furnished at its upper end with a knife-edge J.

K is a lever, one end of which is carried by a pivot or knife-edge M, carried by an arm W, pivoted to a fixed support L; N, a sliding weight upon the other end of this lever; O, a 45 lever pivoted to a fixed support P; R, a sliding weight upon the other end of this lever.

The weights N R may be moved in or out on the levers K O, as may be required for adjustment, and they may be locked to these levers by means of set-screws S. The lever K rests 55 upon and is supported normally in an approximately horizontal position by the knife-edge E, and the lever O is similarly supported upon the knife-edge J.

The pipe A, as has before been stated, is 60 connected with the steam or water space of the boiler, or with the water in a water-column which is acted upon by the steam, and steam or water at the boiler-pressure is carried by this pipe to the chamber B. Should 65 the steam-pressure in the boiler rise beyond a predetermined point, which is determined by the position of the weight N on the lever K, the diaphragm C, the lever K, and the weight N are lifted, and the valve a' is opened 70 and steam or water is admitted from chamber B to pipe F. In the drawings the valve a' is a needle-valve, the needle a being carried by a bushing b, carried by the diaphragm C or by the under part of rod D, which is carried by the diaphragm. A spring c is used to press the point of the needle a against its seat. This spring prevents the needle from carrying an undue weight when the valve is closed. 80

The point of the needle a is adapted to engage a corresponding seat in a bushing d, which is adapted to be screwed into the base-casting T and to project up slightly above the top of this casting into the chamber B, 85 forming a lip e, which prevents sand or similar substances carried by the water into the chamber B from falling into the valve a' or into the pipe F. The pipe F and the cylinder G contain water, which may be water of 90 condensation if steam be carried by pipe A, or if the pipe A carries water, which latter I prefer, the water would be furnished through this pipe. When the steam in the boiler rises above the predetermined point, its pressure, 95 acting directly or through the water in pipe A and chamber B, lifts the diaphragm C and opens valve a', and the pressure of water or steam in chamber B now acting against the water in pipe F causes a certain amount of 100 water to be driven from this pipe into cylinder G and the piston H to be raised thereby.

As the piston H rises its rod I rises and lifts lever O, which latter, through a rod or chain f, lifts the outer end of a lever g, which is attached to and operates the damper h in the 5 stack Y, Fig. 3. The damper is closed by the rising of the lever O to a greater or less extent and checks the draft, and consequently the steam-pressure presently falls, and the needle a' is by the lever K returned to its 10 first or closed position. When the lever K falls and closes the valve a', it engages and pushes down a rod h', Figs. 1 and 2, which passes into a casing i and rests upon a disk j, which is carried by or forms part of a stem k, 15 the upper central part of which carries a conical point or needle l, which is adapted to close a corresponding opening in a passage m, which passes through casing i, and one end of which connects with the interior of cylinder G and the other with the air.

n is a spring which when lever K is lifted lifts stem k and causes cone or needle l to shut off passage M. When the lever K falls, as above stated, it pushes down rod h', which engages disk j and pushes down rod K, causing the cone or needle l to be moved away from its seat and the passage M to be opened. The liquid that is within the cylinder G and above the opening m now runs off through this opening, permitting the piston H to fall, and with it the lever O, and this latter, through the mechanism shown, opens the damper in the 30 stack.

The end of the casing i that is screwed into 35 the cylinder projects preferably slightly into the interior of the cylinder and forms a stop to prevent the piston H falling too low down. The upper end of the rod h' is formed by a cap o, which is screwed on the rod, as shown. 40 This cap may be turned, so as to adjust the length of rod h', as may be found necessary.

U, Fig. 1, is a set-screw carried by the base, casting T, which is adapted to engage and prevent the lever K from falling too low 45 down; V, an adjustable stop carried by the base-casting T, the purpose of which is to limit the upward movement of lever O.

W is an L-shaped lever which is pivoted at X to the standard L; Z, a set-screw carried by the lower arm of this lever.

As has been before stated, the lever K is suspended upon a knife-edge M, which is carried by lever W. By means of the screw Z

the lower or vertical limb of lever W may be moved in or out and the knife-edge M carried by the upper or horizontal limb of this lever, raised or lowered, so as to adjust the lever K properly for engagement by the knife-edge E, carried by standard D.

Having thus described my invention, I claim—

1. In a damper-regulator, in combination, a valve-chamber, a diaphragm closing the top of said chamber, a pipe connecting said chamber and the steam or water space of a steam-boiler, an upwardly-projecting rod carried by said diaphragm, a valve the stem of which is carried by said diaphragm and which is opened when said diaphragm rises and closed when said diaphragm falls, a pipe leading from said pipe to a hydraulic cylinder, said cylinder, a piston and piston-rod within said cylinder, a weighted lever pivoted at one end and resting on said piston-rod, a weighted lever pivoted at one end and resting on the rod carried by said diaphragm, a damper, a connection between said damper and the free end of said former lever, a valve-casing connected to said hydraulic cylinder, a liquid-passage in said casing one end of which is connected to the interior of said cylinder and the other with the air, a stem within said passage, a needle or point carried by said stem, a spring for causing said point to close said liquid-passage when said latter lever rises, 85 and a rod engaging said stem eccentrically the upper end of which is adapted to be engaged by and moved downward upon the falling of the lever carried by the rod on the diaphragm in order to move down said stem in 90 said liquid-passage to open the same in order to permit escape of superfluous liquid, all substantially as and for the purposes set forth.

2. The combination in a relief-valve of a 95 casing, a passage in said casing, a stem in said passage, a disk carried by said stem, a needle or cone-shaped valve carried centrally by said disk, a spring for normally closing said valve, and a rod passing through said 100 casing and engaging the top of said disk substantially as and for the purposes set forth.

AMOS E. BURROWS.
